UNITED STATES PATENT OFFICE.

HENRIETTA BEHR, OF PHILADELPHIA, PENNSYLVANIA.

KITCHEN UTENSIL.

1,390,977.

Specification of Letters Patent. Patented Sept. 20, 1921.

Application filed July 1, 1921. Serial No. 481,743.

To all whom it may concern:

Be it known that I, HENRIETTA BEHR, a citizen of Germany, residing at the city of Philadelphia, county of Philadelphia, and State of Pennsylvania, have invented a certain new and useful Kitchen Utensil, of which the following is a specification.

This invention generally stated relates to kitchen utensils and has more especial relation to a device of this kind which may be employed for pitting cherries.

The leading object of the present invention may be said to reside in the providing of a simple and inexpensive form of device calculated to be held in one hand of the operator to enable the user to stone cherries in a rapid and efficient manner. Other and further objects relate to the provision of general details of construction and arrangement and combination of parts for attaining the results sought by said leading object.

The invention consists of the improvements hereinafter described and finally claimed.

The nature, characteristic features and scope of the invention will be more fully understood from the following description taken in connection with the accompanying drawings forming part thereof in which:

Figure 1, is a perspective view of a device embodying features of the present invention and illustrating the manner of using same.

Fig. 2, is a central sectional view thereof.

Fig. 3, is a fragmentary view illustrating plunger locking means, and

Fig. 4, is a similar view illustrating a detail of construction of the plunger.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings 10 designates a barrel the lower end of which is interiorly provided with an annular shoulder 11 and the upper end of which is exteriorly provided with a lug 12. Slidable through barrel 10 is a

plunger 13 provided at its top with an annular thumb-piece 14. Intermediate the top and bottom of said plunger is a projection which may be a pin 15 driven through the plunger. Coiled around the plunger between said projection and shoulder 11 of barrel 10 is a spiral spring 16. In order to secure the spring pressed plunger against accidental displacement a cap 17 having an inverted L-shaped slot 18 is fitted over the barrel top and caused to engage lug 12 thereon bayonet-joint fashion. The lower end of the plunger is slightly concaved as at 19 and slotted as at 20. The concaved and slotted portions serve to provide a plurality of annular cutting edges and the concaved portion serves to provide a socket for engaging over and impelling a cherry-stone downward through the fruit. Fixed to barrel 10 is an arm of angular formation so that it extends first at right angles to the barrel as at 21, then in parallelism therewith as at 22 and terminates in a part 23 which curves in a direction toward and below the barrel. Carried by the curved end 24 of said arm is a dish-shaped receptacle 25 having an aperture 26 therethrough in alignment with plunger 13. Fixed to barrel 10 intermediate the above described arm and cap 17 is a finger-piece 27 which extends laterally upon each side of the barrel. The ends of the finger-piece are slightly curved downwardly to more readily accommodate the fingers of the user.

In practice the user holds the device in one hand and operates the plunger thereof with the thumb employing the other hand for placing the fruit to be pitted within receptacle 24. In use the index finger and middle finger of the operating hand are placed beneath finger piece 27. One movement of the plunger serves to expel a stone from a cherry, the stone passing through aperture 26 of the receptacle.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without

departing from the spirit or scope of the invention or sacrificing any of its advantages.

What I claim is:—

- 5 1. A device of the character stated comprising a barrel provided with a finger-piece, a spring-pressed plunger mounted within said barrel one end of which is provided with a thumb-piece and the other end with a fruit penetrating and stone impelling portion and a dish-shaped receptacle carried by said barrel which receptacle is provided with an aperture in alignment with said plunger.
- 10 2. A device of the character stated comprising a barrel provided with a finger-piece, a spring pressed plunger mounted within said barrel one end of which is provided with a thumb-piece and the other end with a fruit penetrating and stone impelling portion, a dish-shaped receptacle having an apertured bottom carried by said barrel and a cap having a bayonet-joint connection with said barrel for maintaining said plunger in position.
- 15 3. A device of the character stated com-

prising a barrel provided with a finger-piece, a spring pressed plunger mounted within the barrel one end of which is provided with a thumb-piece and the other end with a fruit penetrataing and stone impelling portion, an arm fixed to said barrel which arm extends to one side of said barrel and terminates in a portion which curves toward said barrel and a dish-shaped receptacle having an apertured bottom carried by the curved end of said arm.

4. A device of the character stated comprising a barrel provided with a finger-piece, a plunger mounted within the barrel one end of which is provided with a thumb-piece and the other end with a fruit penetrating and stone impelling portion, a spring within said barrel and coiled around said plunger for returning said plunger to normal position and a dish-shaped receptacle having an apertured bottom carried by said barrel.

In testimony whereof I have hereunto signed my name.

HENRIETTA BEHR.
